CLAIM

The ornamental design for an inhalant dispenser, as shown and described.

DESCRIPTION

FIG. 1 is a perspective view of an inhalant dispenser.

FIG. 2 is a front view of the inhalant dispenser shown in FIG. 1.

FIG. 3 is a rear view of the inhalant dispenser shown in FIG. 1, opposite the front view shown in FIG. 2.

FIG. 4 is a side view of the inhalant dispenser shown in FIG. 1.

FIG. 5 is a side view of the inhalant dispenser shown in FIG. 1, opposite of the side shown in FIG. 4.

FIG. 6 is a top view of the inhalant dispenser shown in FIG. 1.

FIG. 7 is a bottom view of the inhalant dispenser shown in FIG. 1, opposite the top view shown in FIG. 6; and, FIG. 8 is a partially exploded view of the inhalant dispenser shown in FIG. 1.

The dot-dashed broken lines in the drawings illustrate the bounds of the inhalant dispenser that form no part of the claimed design. All other broken lines illustrate portions of the inhalant dispenser that form no part of the claimed design.

1 Claim, 6 Drawing Sheets
